US00D784665S

(12) **United States Design Patent** (10) **Patent No.:** **US D784,665 S**
(45) **Date of Patent:** **** Apr. 25, 2017**

(54) **TOE CAP FOR FOOTWEAR**

(71) Applicant: **TBL Licensing LLC**, Wilmington, DE (US)
(72) Inventor: **Thomas Yeh**, Newmarket, NH (US)
(73) Assignee: **TBL Licensing LLC**, Stratham, NH (US)

(**) Term: **15 Years**

(21) Appl. No.: **29/529,466**

(22) Filed: **Jun. 8, 2015**

(51) **LOC (10) Cl.** **02-99**
(52) **U.S. Cl.**

USPC **D2/946; D2/972**
